UNITED STATES PATENT OFFICE

WILLIAM JAMES CHILES, OF WIGGINS, MISSISSIPPI

SWITCH

Application filed May 1, 1928. Serial No. 274,325.

This invention relates to switches and more particularly to a switch providing a universal gravity control for motors and more particularly for motors operating the controls of a dirigible vehicle, such as an aeroplane, submarine or the like to maintain the vehicle upon an even keel.

An important object of the invention is to provide a construction such that the switch 10 will serve not only as an automatic control but as a level, giving visual indication of displacement of the vehicle from an even keel.

A still further object of the invention is 15 to provide a construction of this character permitting convenient combination of the switches controlling longitudinal and transverse displacement.

A further object of the invention is to 20 provide a device of this character which may be readily and cheaply manufactured, which may be readily attached to the vehicle and which will be durable and efficient in service.

These and other objects I attain by the 25 construction shown in the accompanying drawings, wherein for the purpose of illustration is shown a preferred embodiment of my invention and wherein:—

Figure 1 is a rear elevation of a switch 30 constructed in accordance with my invention;

Figure 2 is a side elevation thereof;

Figure 3 is a section on the line 3—3 of Figure 1;

Figure 4 is a plan view of the switch;

Figure 5 is a vertical sectional view thereof.

Referring now more particularly to the drawings, the numeral 10 generally designates a tube, the central portion of the lower wall of which is depressed, as at 11, to provide a basin for the reception of conducting fluid, designated at 12. This fluid is preferably mercury or some other heavy substance 40 which will move smoothly in the tube as the tube is oscillated upon its longitudinal axis. The tube is longitudinally divided by a vertical partition 13 which terminates short of the ends of the tube. In the ends of the 45 tube are inserted threaded disks 14 of in-

sulating material which seal both to the walls of the tube and to the end of the partition. Each disk has directed through the upper portion thereof contacts 15 and 16, of which similar contacts at opposite ends of 55 the tube project into opposite ends of the same chamber. Within the depression of the tube and in each chamber is disposed a contact element 17, the binding posts 18 of which extend through the wall of the tube. 60

In the construction of the completed switch, two of these tubes are employed arranged in superimposed relation with their axes at right angles to one another. A casing is provided for the tubes which is formed 65 in sections 19, 20 and 21. The section 20 or intermediate portion forms a casing for one-half of each of the tubes, the casing 19 forms the lower half of the casing of the lower tube and the section 21 the upper half 70 of the casing of the upper tube.

The casing section 21 has at its center one element 22 of a ball and socket joint, the other element 23 of which is constructed to permit ready attachment thereof to the vehicle. The element 23 is so constructed that it may clamp upon the element 22 to hold the completed switch in a desired adjusted position. The casing sections 20, 21 and 19, 75 20 are notched at their meeting edges which 80 are disposed at the level of the fluid of these tubes when the tubes are horizontally positioned, so that this fluid may be observed through the resulting openings 24 to give a visible indication to the operator of the 85 level of the vehicle. The construction illustrated is that where the lower tube is employed to indicate transverse inclination of the vehicle. The tube employed to indicate transverse inclination might be arranged 90 uppermost, if so desired. In Figure 3, I have indicated the manner of connecting this switch with a motor to effect a reversal thereof. In this view, a source of energy B is shown as connected across the terminals 95 of the tube. The field F of the motor M has each terminal thereof connected with the contact 15 at one end of the tube and the contact 16 at the opposite end thereof. In making the connections of the second tube 100

of the switch, bus wires 26 are employed to connect the binding posts 18 thereof with the binding posts 18 of the first tube.

It will be obvious that upon inclination 5 of the tube, which will cause the fluid 12 to connect the contact 17 with the contacts 15 and 16 at one end of the tube, the field will be energized and the motor will rotate in one direction. When, however, the liquid 10 engages the contacts 15 and 16 at the opposite end of the tube, the energization of the field F will be such that the motor M will operate in the opposite direction.

With this motor connected with controls, 15 such as the elevators of an aeroplane (not herein shown), these controls will be shifted in opposite directions upon inclination of the tube in opposite directions. It will be obvious that by properly connecting the motor, the 20 controls may be positioned to correct inclination of the aeroplane and bring the same to a level keel.

A switch of this character may be readily 25 and cheaply constructed and may be made of such size that it may be conveniently disposed at a desired point in the cockpit of a plane. It will also be obvious that the construction hereinbefore set forth is capable of a certain range of change and modification without 30 materially departing from the spirit of the invention and I accordingly do not limit myself to such specific structure except as hereinafter claimed.

I claim:—

35 1. In a switch for the purpose described, a pair of horizontal tubes disposed at right angles and each provided with a longitudinally extending vertical partition forming in the interior of the tube a pair of compartments, 40 means sealing the tube to the partition at the ends of each tube, a contact extending into each end of each compartment, a centrally located contact in each compartment, a conducting liquid within the compartment and when 45 the tubes are horizontal engaging only the central contact of the compartment, a rigid connection between the tubes, means for securing said tubes to a supporting surface permitting universal adjustment of the tubes 50 with relation to said surface, said means connecting said tubes comprising a casing having openings formed in the walls thereof permitting observation of the liquid within the tubes.

55 2. In a switch for the purpose described, a pair of horizontal tubes disposed at right angles and each provided with a longitudinally extending vertical partition forming in the interior of the tube a pair of compartments, 60 means sealing the tube to the partition at the ends of each tube, a contact extending into each end of each compartment, a centrally located contact in each compartment, a conducting liquid within the compartment and 65 when the tubes are horizontal engaging only

the central contact of the compartment, and a casing enclosing said tubes formed in a plurality of sections adapted to be assembled about the tubes to rigidly connect the same, one of said sections having a spherical head 70 secured thereto, and a split socket for engagement with said head and having means whereby it may be attached to a supporting surface, and means associated with said socket for clamping the socket upon said spherical head. 75

3. In a switch for the purpose described, a pair of horizontal tubes disposed at right angles and each provided with a longitudinally extending vertical partition forming in the interior of the tube a pair of compartments, 80 means sealing the tube to the partition at the ends of each tube, a contact extending into each end of each compartment, a centrally located contact in each compartment, a conducting liquid within the compartment and when the tubes are horizontal engaging only the central contact of the compartment, a casing enclosing said tubes formed in a plurality of sections adapted to be assembled about the tubes to rigidly connect the same, one of said sections having a spherical head 85 secured thereto and a split socket for engagement with said head and having means whereby it may be attached to a supporting surface, and means associated with said socket for clamping the socket upon said spherical head, the abutting edges of said sections being at the approximate level of the liquid within the tubes, said abutting edges having notches 90 formed therein providing openings through 100 which the liquid of the tubes may be observed.

4. In a switch for the purpose described, a pair of horizontal tubes disposed at right angles and each provided with a longitudinally extending vertical partition forming in the interior of the tube a pair of compartments, 105 means sealing the tube to the partition at the ends of each tube, a contact extending into each end of each compartment, a centrally located contact in each compartment, a conducting liquid within the compartment and when the tubes are horizontal engaging only the central contact of the compartment, a rigid connection between the tubes, means for securing said tubes to a supporting surface 110 permitting universal adjustment of the tubes with relation to said surface, and an electrical connection between the centrally located contact of each compartment and the centrally located contact of the corresponding compartment of the other tube. 115

5. In a switch for the purpose described, a pair of horizontal tubes disposed at right angles and each provided with a longitudinally extending vertical partition forming in the interior of the tube a pair of compartments, 120 means sealing the tube to the partition at the ends of each tube, a contact extending into each end of each compartment, a centrally located contact in each compartment, a conduct- 125
